UNITED STATES PATENT OFFICE.

HENRY M. SHEER, OF QUINCY, ILLINOIS, ASSIGNOR TO WILSON ARBOGAST, OF ALLENTOWN, PENNSYLVANIA.

HEATING SYSTEM FOR INCUBATORS AND BROODERS.

1,128,535.

Specification of Letters Patent. Patented Feb. 16, 1915.

Application filed August 19, 1913. Serial No. 785,550.

To all whom it may concern:

Be it known that I, HENRY M. SHEER, a citizen of the United States, residing at Quincy, in county of Adams and State of Illinois, have invented certain new and useful Improvements in Heating Systems for Incubators and Brooders, of which the following is a specification.

My invention relates to an improvement in heating systems for incubators and brooders.

The object of my invention is to provide a heating system which takes advantage of the temperature-raising properties of both hot water and steam.

A further object is to so arrange the system that a maximum of heat is obtained from the coil or circulating tube and the amount of water heated. And a still further object is to so construct and install the system that the heat will be distributed evenly throughout the egg chamber and the temperature in that chamber will be the same at all points.

This invention consists in certain other novel features of construction and combinations of parts which will be hereinafter fully described and pointed out in the claims.

In the accompanying drawings:—Figure 1 is a view in top plan with the cover removed to better illustrate the position and arrangement of the circulating tubes, Fig. 2 is a longitudinal vertical sectional view 35 through the incubator to illustrate the relation of the heating coil to the circulating tubes, Fig. 3 is vertical sectional view on the line 3—3 of Fig. 2, and Fig. 4 is an enlarged detail view of the vacuum-controlled water supply to the heating coil.

The box or body A of the incubator to which the system is illustrated as applied is constructed in the usual manner to insulate the egg-chamber against sudden changes of temperature due to the rise and fall of the atmospheric temperature, and at its front is provided with a door 1. The body A may have legs secured thereto or may be supported in any approved manner, and has the usual egg-tray 2 constructed to be received in the hatching-chamber 3 thereof.

A jacket B which forms a chimney for the lamp C carried thereby is secured to the body A, preferably at one end.

An exhaust flue 4 is provided through the

center of the jacket B and a heating-coil 5 is located within the jacket around the flue 4.

It is well known that water, when heated in a coil, will circulate, the hot water rising in the coil whereas the cold water goes to the bottom of the coil; and, further, that steam being lighter than the heated water from which it passes off, forms a vapor above the water, and it is to take advantage of this principle and the superior heating action of steam that I have arranged my system.

In use the exhaust flue 4 is normally closed by a damper 25 and all of the heat from the lamp passes up through the jacket B and out through the openings 28, 28 provided in the upper part thereof. This jacket is preferably made of cast iron or other heat retaining material and is tapered slightly toward the top to cause the heat to be directed fully against and around the turns of the coil 5.

The circulating system within the hatching-chamber comprises a central tube 6, and side tubes 7 and 8. At the inner end, the tubes 7 and 8 are connected together by a cross-tube 9, and the passage from one of these tubes to the other is left free and unobstructed. At the outer end, a tube 10 connects tubes 7 and 8. The tube 6 is secured at its outer end around the tube 10, and opens into tube 6, as at 11. Cross-pipes 12, 12, of less diameter than the tubes 6, 7, and 8 are connected between the tubes 6 and each of the tubes 7 and 8 at a point about midway up the side of these tubes. The heating-coil 5 at its upper end passes through the tube 9, and its free end 13 extends for some distance into the tube 6. The lower end of the heating-coil is connected at 14 to the lower side of the tube 9 approximately at the longitudinal center thereof.

Assuming that the coil 5 has been filled with water and the lamp is burning:—The water in the coil is heated until steam is generated, and this heating causes the water to circulate through the coil in an upward direction passing out of the coil at the end 13 into the tube 6. The water supply is so arranged that the water in the heating tubes is maintained at an even level, which is below the opening into the cross-pipes 12, as indicated by the dotted lines in Fig. 2 and the opening 11 from the tube 6 into the tube 10 is made of sufficient height to permit the passage of the water contained in the tube 6.

but preclude the passage of steam into the tube 10. The steam rises from the water supplied to the tube 6, and passes through the cross-pipes 12 to tubes 7 and 8. The hot water circulates in the direction indicated by the arrows in Fig. 1 from the tube 6 through each end of tube 10 to the side tubes 7 and 8 respectively, and back to tube 9 from which it passes through the return end 14 of the coil back to the heating-coil around the lamp where it is again heated and the circulation caused to continue.

It will, of course, be understood that steam will rise from the water in all parts 15 of the tubes 6, 10, 7, 8, and 9, but the production of steam will be perhaps greater in the tubes 6 and 10, and the rise of steam materially lessened as the water reaches the tubes 7 and 8. It is desirable that the same 20 amount of steam be maintained in each of the tubes, and it is for this purpose that the cross-pipes 12 are provided. They, positioned as they are above the level of the water, carry the steam from the central tube 25 6 to the side tubes 8 and 7, and maintain the steam constant in each of the tubes.

As a means of permitting the escape of the steam and relieving the pressure in the circulating tubes, vents 15, 15, are provided 30 in the upper part of the tube 9 on each side of the connection at 14 of the return-end of the heating-coil, or at any other suitable point. This escaping steam supplies moisture to the egg-chamber, which maintains 35 the air at the proper degree of humidity.

With the arrangement as described, the temperature of the water in the several tubes of the circulating system would be practically the same throughout, but a greater 40 heat radiating surface is provided adjacent the central tube 6 by reason of the cross-pipes 12 passing from each side thereof; and under ordinary conditions there would be danger of the egg-chamber being over-heated at this point. To provide against 45 this condition, I position a deflector 16 above the circulating-tubes, and, as better shown in Fig. 3, this deflector is raised at that point over the tube 6, and slopes gradually 50 down from this point to the point where it abuts against the sides of the body A. With the deflector formed in this manner, the heat at the center of the circulating system can radiate up, and it is then directed back 55 against the contents of the egg-tray, whereas at the sides the deflector is in close proximity to the tubes of the circulating system, and the radiation of heat from these tubes must consequently be in a downward 60 direction. By this arrangement of the deflector with respect to the tubes of the circulating system, an even temperature is established and maintained throughout the incubating chamber.

65 As a means of maintaining the proper

amount of water in the heating-coil 5, I have provided a supply-pipe 17 which is connected preferably at the lowest point in the return-end 14 of this coil, and a bell 18 is connected with the upper end of the supply-pipe 17. A water reservoir 20 is supported above the bell 18, and has a tube 21 secured air tight around the mouth thereof. The reservoir 20 is supported a sufficient height above the bell 18 that the tube 21 extends down to the height at which the water-level is to be established. When the water in the bell 18 is at the proper height, the end of the tube 21 is closed, or sealed, and the water cannot consequently flow 70 from the reservoir 20, but as the water-level is reduced in the bell 18, due to evaporation or to any other cause, the mouth of the tube 21 is opened to the air, and as air can then pass into the reservoir 20, through 75 holes 27, bell 18, and tube 21 the water will flow into the bell and raise the level again to normal.

As a means of draining the coil 5, when the incubator is not in use, an outlet 22 controlled by a valve 23 is provided at the lowest point in the coil.

It will be seen that a boiler or any other suitable form of heating-tank might be used in this connection and with equally good results, the heating-coil being merely shown as one means of attaining the desired result.

A thermostat 24 is provided in the incubating chamber, and is connected to operate the damper 25, which controls the opening 100 from the exhaust flue 4.

While my invention has been described for use with an incubator, it is evident that the desired function would be accomplished if the device was installed in a brooder or 105 in a combination incubator and brooder.

From the foregoing, it will be seen that I have provided a system which accomplishes a successful heating action with a minimum of heating element and a minimum of fuel 110 consumption, as the structure takes advantage of the better heating action of steam and the heat-maintaining properties of water.

More or less slight changes might be 115 made in the form and arrangement of the several parts described without departure from the spirit and scope of my invention, and hence I do not wish to be limited to the exact construction herein set forth.

I claim:

1. A heating system comprising a central and side tubes spaced apart, means forming communication between said tubes at one end thereof, cross-pipes connected with the tubes sufficiently above the bottom of the latter to conduct steam therethrough rather than water, water-heating means, a supply pipe for said water-heating means arranged to conduct the water to and dis- 120

charge it into said central tube, and to maintain a low level of water in the several tubes of the system, and a return-pipe from the tubes to the heating-means.

- 5 2. A system of the type described comprising a water heater, a heating system comprising a central and side tubes spaced apart, means forming communication between said tubes at one end thereof, cross 10 pipes connected between the central tube and side tubes constructed and adapted to conduct steam, a water supply pipe from said heater to said central tube adapted to maintain a low water level in said tube, the 15 communication between the central tube and the side tubes at the said end thereof so arranged that water only may pass, a return pipe from the tubes of said system to the heater for conducting the water from said 20 tubes back to be heated in the heater, and steam outlets to permit the circulation of steam through said tubes and to supply moisture to said chamber.
3. A system of the type described com- 25 prising a water heating coil, a heating system comprising a central and side tubes spaced apart, means forming communication between said tubes at one end thereof,

cross pipes connected between the central tube and side tubes, a water supply pipe 30 from said heating coil to said central tube, adapted to maintain a low water level in said tube, the communication between the central tube and the other tubes at the said end thereof so arranged that water only 35 may pass, and the communication of the cross pipes so formed that steam only may pass, a return pipe from the tubes of said system to the coil for conducting the water from tubes back to be heated in the coil, 40 steam outlets in the upper surface of at least one of the tubes to permit the circulation of the steam through said tubes and to supply moisture to said chamber, a deflector located above said circulating system to 45 equalize the deflection of heat downwardly into the chamber, a lamp for heating the coil, and a jacket for confining the heat of the lamp.

In testimony whereof I affix my signature, 50 in the presence of two witnesses.

HENRY M. SHEER.
